UNITED STATES PATENT OFFICE.

HARRY O. RUGH, OF SANDWICH, ILLINOIS, ASSIGNOR TO SANDWICH ELECTRIC COMPANY, OF SANDWICH, ILLINOIS.

SIGNALING SYSTEM.

1,028,790.

Specification of Letters Patent.

Patented June 4, 1912.

Original application filed September 1, 1910, Serial No. 580,068. Divided and this application filed September 14, 1911. Serial No. 649,355.

To all whom it may concern:

Be it known that I, HARRY O. RUGH, a citizen of the United States, residing at Sandwich, in the county of Cook and State 5 of Illinois, have invented a certain new and useful Improvement in Signaling Systems, of which the following is a full, clear, concise, and exact description, reference being had to the accompanying drawings, forming 10 a part of this specification.

My invention relates to circuit controlling a paratus and is of more particular service in connection, for instance, with call boxes for selective signaling systems, al- 15 though of course not so limited.

My invention herein is a divisional application of a co-pending application of mine, Serial No. 580,068, filed Sept. 1, 1910 in which a complete call box is set forth 20 and in which my present invention was originally disclosed.

My invention herein concerns itself with a movable member of a call box in association with which switching elements are pro- 25 vided of a certain character which control certain circuit changes. The switch elements are frictionally associated with the movable element and this frictional engagement permits a very simplified structure of 30 devices of this character.

I will explain my invention more in detail by referring to the accompanying drawing setting forth one embodiment thereof in which:

Figure 1 is a front view of a call box constructed in accordance with my invention; Fig. 2 is an interior view of the call box setting forth the structural arrangement of my invention, and: Fig. 3 is a diagrammatic 40 view setting forth the circuit arrangements.

The call box of my invention has a cover plate 1 associated with a box 2, which cover plate carries a shaft 3 mounted therein. On the front face of the cover plate is rotatably mounted a disk 4 which is secured to the shaft 3. A handle 5 loosely mounted on the shaft 3 provided with a knob 6 is adapted to be set at any angular position with relation to the disk 4 and is adapted to 45 rotate said disk 4 a given angular distance depending upon where the button 6 is placed with relation to the openings 7 in the said disk 4. The shaft 3, referring more particularly to Fig. 2, carries at its opposite ex-

tremity a toothed element 8 secured thereto by means of a set screw 9. A clockwork mechanism carried by the framework 10 and of ordinary construction, drives the shaft 3 after the shaft has been moved in a direction against said clockwork and a governor 12 controls the speed of rotation. A spring 13 is adapted for engagement with the teeth 14 of the element 8 and is suitably mounted upon an insulating bracket 15. The spring 13 in association with the movable element 8 controls the circuit through a relay 16, which circuit also includes a battery 17. The relay in response to impulses actuates an armature 18 to transmit the battery impulses from a battery 19 over a line circuit comprising the conductors 20 and 21. The handle 5 when rotating the plate 4 rotates the movable element 8 into a position from which the clockwork rotates it, and during this restoring rotation of the element 8, the substation selecting impulses are transmitted.

During the time that the element 8 is being set to its initial call sending position, it is of advantage that a long impulse be transmitted in order to place the substation signal receiving devices in condition to receive the impulses which are later transmitted upon the reverse movement of the element 8, and to accomplish the sending of this long impulse I provide two springs 22 and 23 which are independently mounted on an arm 24 and which when in a closed position close circuit through the relay 16 so that an impulse is transmitted. The novel structural features of these circuit elements are the subject matter of my present invention. The spring 23 carries a frictional element 25, which frictional element engages the movable element 8. Now when the element 8 is rotated "referring to Fig. 3" in a contra clockwise direction, which is the setting operation, then the friction between the elements 8 and 25 causes a flexure of the spring 23 so that it engages spring 22 and closes circuit through the relay 16. Now when the clockwork rotates the element in a clockwise direction, referring to Fig. 3, then the friction between the elements 8 and 25 moves the spring 23 away from the spring 22 and circuit through the relay 16 is broken except as it is periodically made when teeth 14 engage the spring 13.

This frictional control of the circuit changing springs 22 and 23 serves to provide a very simple and efficient controlling device which is of service in this and of course 5 other connections.

Having thus described one form which my invention may take, what I claim as new and desire to secure by Letters Patent is:

- 10 1. A call box having a circuit controlling element, contact making devices mounted independently of said element, controlling means for said contact making devices also mounted independently of said element and having frictional engagement with said element, whereby movement of said element in one direction will establish certain circuit conditions, and a movement in the opposite direction of the element will establish different circuit conditions.
- 15 2. A call box having a movable circuit controlling element, contact making devices mounted independently of said element, controlling means for said contact making devices mounted on one of said devices and having frictional engagement with said element, whereby movement of said element in one direction will establish certain circuit conditions, and a movement of the element in the opposite direction will establish different circuit conditions.
- 20 3. A call box having a movable circuit controlling element, contact making springs mounted independently of said element, controlling means for said contact making springs also mounted independently of said element and having frictional engagement with said element, whereby movement of said element in one direction will establish certain circuit conditions, and a movement of the element in the opposite direction will establish different circuit conditions.
- 25 4. A call box having a movable circuit controlling element, contact making springs mounted independently of said element, controlling means for said contact making springs mounted on one of said springs and having frictional engagement with said element, whereby movement of said element in one direction will establish certain circuit conditions, and a movement of the element in the opposite direction will establish different circuit conditions.
- 30 5. A call box having a rotatable circuit controlling element, contact making devices mounted independently of said element, controlling means for said contact making devices also mounted independently of said element and having frictional engagement with said element, whereby movement of said element in one direction will establish certain circuit conditions, and a movement in the opposite direction of the element will establish different circuit conditions.
- 35 6. A call box having a rotatable circuit controlling element, contact making devices mounted independently of said element, controlling means for said contact making devices mounted on one of said devices and having frictional engagement with said element, whereby movement of said element in one direction will establish certain circuit conditions, and a movement in the opposite direction will establish different circuit conditions.
- 40 7. A call box having a rotatable circuit controlling element, contact making springs mounted independently of said element, controlling means for said contact making springs also mounted independently of said element and having frictional engagement with said element, whereby movement of said element in one direction will establish certain circuit conditions, and a movement of the element in the opposite direction will establish different circuit conditions.
- 45 8. A call box having a rotatable circuit controlling element, contact making springs mounted independently of said element, controlling means for said contact making springs mounted on one of said springs and having frictional engagement with said element, whereby movement of said element in one direction will establish certain circuit conditions, and a movement of the element in the opposite direction will establish different circuit conditions.
- 50 9. A call box having a rotatable circuit controlling element, contact making devices mounted independently of said element, controlling means for said contact making devices also mounted independently of said element and having frictional engagement with said element, whereby movement of said element in one direction will establish certain circuit conditions, and a movement in the opposite direction of the element will establish different circuit conditions.

In witness whereof, I hereunto subscribe my name this 31st day of August, A. D., 1911.

HARRY O. RUGH.
